UNITED STATES PATENT OFFICE.

JAMES S. THOMPSON, OF PELHAM, NEW YORK.

BRAKE-SHOE MOLD.

Application filed July 20, 1923. Serial No. 652,778.

To all whom it may concern:

Be it known that I, JAMES S. THOMPSON, a citizen of the United States, residing at Pelham, in the county of Westchester and State of New York, have invented certain new and useful Improvements in Brake-Shoe Molds, of which the following is a specification.

This invention relates to the manufacture of brake shoes in permanent molds, and its object is to provide a novel means of simple form for suspending the reinforcing back, the attaching lug and the core for forming the opening in the attaching lug in proper position in the mold cavity for embedding the back and the lug in the shoe during the casting operation.

In the accompanying drawings illustrating a selected embodiment of the invention—
20 Fig. 1 is a transverse sectional view on the line 1—1 of Fig. 2.

Fig. 2 is a longitudinal sectional view on the line 2—2 of Fig. 1.

Fig. 3 is a horizontal sectional view on the line 3—3 of Fig. 2.

Referring to the drawings, the mold comprises a metal drag 4 and a two-member metal cope comprising the left member 5 and the right member 6 hinged at 7 to the relatively fixed drag and adapted to be secured in closed position by the clamps 8. In the particular adaptation of the invention illustrated in the drawings, the mold cavity 9 has a refractory facing 10 which prevents the metal of the mold from chilling the casting. The invention can be just as well employed in metal molds wherein chilled shoes are cast, as will be readily understood.

40 The reinforcing back 11 and the steel lug 12 with the core 13 for forming the opening in the lug are preferably assembled as a unit and inserted in the left member of the cope when the cope members are in open position as shown in broken lines in Fig. 1, or when the left member of the cope is in closed position and the right member of the cope is in open position. The mold cavity has a recess 9' to accommodate the lug and the core, and since the parting line between the two cope members extends longitudinally of the mold and is preferably located centrally of the mold cavity, one half of said recess is in the left cope member and one half is in the right cope member, so that when the right cope

member is open the back unit can be readily inserted in that part of the mold cavity and its recess in the left cope member.

To hold the back unit in place in the left cope member while the right cope member is being closed and during the casting operation, I provide wires 14 which extend through grooves 15 formed partly in each of the cope members, the wires being provided with heads of any suitable description for engaging with the reinforcing back and with the top of the cope. I prefer to make the wires with elongated heads 16 to engage the reinforcing back transversely and with heads 17 primarily to engage the top of the left cope member 5. When the back unit is arranged in that part of the mold cavity in the left cope member 5 the wires 14 will be inserted in the grooves 18 in the reinforcing back and then turned until the heads 16 extend transversely across the openings 18 and engage the underside of the back. The head 17 should be substantially aligned with the head 16 so that when the head 16 is in operative engagement with the back, the head 17 will be in operative engagement with the cope member 5. The head 17 may be turned up at 17' to permit the right cope member 6 to be closed without disturbing the back unit or the wires, and also to form a gripping piece by which the wires can be easily turned to operative position. After the wires have been arranged in their operative position as shown, the right cope member 6 can be swung to closed position, and even if it engages the grip member 17' it will not disarrange the assembly because the latter will yield sufficiently to permit the right cope member 6 to be closed and without disturbing the back unit.

My invention provides a simple, easily operated and convenient means for suspending and securing the reinforcing back, attaching lug and core for forming the opening in the attaching lug in their proper positions in the mold cavity preliminary to and during the casting operation. A pouring gate 19 and sand vents 20 are conveniently located in the cope. The wires can be readily adjusted in position to engage the back of the cope member 5 while the cope member 6 is open, and they will securely hold the back unit while the cope member 6 is being closed and during the casting operation.

My invention can be employed for making castings other than brake shoes and I consider myself entitled to make all such changes in the form, construction and arrangement of parts as may be necessary or desirable for this purpose, and for making different kinds, shapes and sizes of brake shoes, which fairly fall within the scope of the following claims.

10 I claim:

1. A permanent mold for making castings, comprising a drag and a cope having a mold cavity therein, the cope adapted to be opened to permit the insertion of a unit therein and 15 also being provided with grooves extending therethrough and communicating with the mold cavity, and wires extending through said grooves and having angularly disposed means adapted to be turned to operatively 20 engage the unit and the cope to suspend the unit in the mold cavity.

2. A permanent mold for making castings, comprising a drag and a cope having a mold cavity therein, the cope adapted to be opened 25 to permit the insertion of a unit therein and also being provided with grooves extending therethrough and communicating with the mold cavity, and single wires extending through said grooves and having angularly 30 disposed means to engage said unit and said cope for suspending the unit in the mold cavity.

3. A permanent mold for making castings, comprising a drag and a cope having a mold 35 cavity therein, the cope adapted to be opened to permit the insertion of a unit therein and also being provided with grooves extending therethrough and communicating with the mold cavity, and wires extending through 40 said grooves and having elongated heads adapted to be arranged transversely of the unit to engage said unit and the cope for suspending the unit in the mold cavity.

4. A permanent mold for making castings, 45 comprising a relatively fixed drag and a two-member cope having its members hinged to the drag, with the parting line extending longitudinally of the mold and substantially centrally of the mold cavity, said cope having grooves extending therethrough and 50 communicating with the mold cavity, said grooves being formed partly in one cope member and partly in the other cope member, and means extending through said 55 grooves and engaged with a unit and the cope for suspending the unit in the mold cavity.

5. A permanent mold for making castings, comprising a drag and a cope having a mold cavity therein, said drag being relatively 60 fixed and said cope comprising two members hinged to the drag and having grooves formed partly in one member and partly in the other member and extending through the cope and communicating with the mold cavity, and wires extending through said 65 grooves and engaged with a unit and the top of the cope to suspend the unit in the mold cavity, said wires having lower heads to engage the back and upper heads to engage one member of the cope.

6. A permanent mold for making castings, comprising a drag and a two-member cope having a mold cavity therein, the members of the cope being hinged to the drag, said 75 cope having grooves extending therethrough and communicating with the mold cavity, and wires extending through said grooves and having on one end a head to engage a unit and on the other end a head to engage 80 the cope and a gripping piece.

7. A permanent mold for making castings, comprising a drag and a two-member cope having a mold cavity therein, said cope members being movable independently and 85 relatively to the drag to open the mold, and means extending through the cope for supporting in the mold cavity the parts which are to be embedded in the casting.

8. A permanent mold for making castings, 90 comprising a drag and a two-member cope having a mold cavity therein, said cope members being movable independently and relatively to the drag to open the mold, and means detachably engaged with one of the 95 cope members for supporting in the mold cavity the parts which are to be embedded in the casting.

9. A permanent mold for making castings, comprising a drag and a two-member cope 100 having a mold cavity therein, said cope members being movable independently and relatively to the drag to open the mold, and means extending through the cope and engaged with both members thereof for supporting in the mold cavity the parts which are to be embedded in the casting.

10. The combination with a permanent mold for making castings, comprising a drag and a cope having a mold cavity therein, of 105 a wire for suspending a unit in the mold cavity and having on each end a transversely extending head.

JAMES S. THOMPSON.
